UNITED STATES PATENT OFFICE.

GEORGE B. CANADA, OF MEMPHIS, TENNESSEE, ASSIGNOR OF ONE-HALF TO JAMES B. HOLLEY, OF MEMPHIS, TENNESSEE.

COMB.

Application filed September 11, 1924. Serial No. 737,115.

This invention relates to new and useful improvements in combs, and particularly to combs adapted for use by barbers.

One object of the invention is to provide a comb of such construction that the danger of cutting off too much hair is reduced to a minimum.

Another object is to provide a comb of this character which obviates the usual cramping twist of the wrist of the operator.

Other objects and advantages will be apparent from the following description when taken in connection with the accompanying drawing.

15 In the drawing:

Figure 1 is an elevation of a comb made in accordance with the present invention.

Figure 2 is an end view of the same.

Referring particularly to the accompanying drawing, 10 represents the back of the comb, and 11 and 12 the coarse and fine teeth, respectively, the entire comb structure being longitudinally tapered in the direction of the fine teeth, as clearly seen in the elevation, Figure 1.

Upon reference to the end view, Figure 2, it will be seen that the body of fine teeth are inclined on one direction, out of the plane of the back, while the body of coarse teeth are inclined in the opposite direction, out of the plane of the back. In the manufacture of the comb the opposite end portions of the back of the comb are given twists in the opposite directions, whereby the two sets of teeth will extend obliquely with respect to each other, and to the longitudinal axis of the back. It will also be noted, that the teeth of each set lies in the plane of the corresponding portion of the back, or that portion to which they are attached. This twist is clearly seen in the center of the back of the comb, in Figure 1. This provides a considerable space between the innermost of the coarse and fine teeth, whereby to permit easy manipulation of the comb around the ears of the sitter.

With the ordinary comb, wherein the teeth lie in the same plane as that of the back, it

requires a twist of the wrist of the operator, when using the comb in a hair cutting operation, with the result that the wrist and hand become cramped. With the present comb the incline of the body of teeth permits the natural position of the hand and wrist, while manipulating the comb. 50 Furthermore, with the ordinary comb it is difficult to gage the amount of hair which shall project from the teeth of the comb, and which is to be cut off. With the present comb, the operator holds the same in the ordinary and natural position, which disposes the teeth at such an angle to the surface of the head as to permit the proper amount of hair to project through the teeth. Thus the operation of cutting is reduced to a simple 60 and easy operation, and without danger of the operator cutting off too much hair.

The comb illustrated in the present drawing is especially adapted for right-handed barbers, when making a full haircut, and is 65 adapted to be used in the left hand of a left-handed barber for making a close cut. To provide for making a close cut, by a right-handed barber, the comb will be constructed with the teeth inclining in the opposite direction to that illustrated.

Furthermore, the use of the comb, in making a close cut, permits the barber to easily and neatly remove the marks left by the clipper. Also, the comb permits easy access 70 to the hair around the ears, and in the depressions in the neck.

What is claimed is:

1. A comb having a series of teeth extending radially of the axis of the back of the comb in one direction, and a series of teeth extending radially of the axis of the back of the comb and obliquely with respect to the first teeth, the innermost teeth of the two series diverging with relation to each other to provide a gap for the sitter's ear.

2. A comb including a back having two series of teeth, one series of teeth extending in a plane obliquely to that of the other teeth and in the plane of the corresponding portion of the back, the innermost teeth of

the two series diverging both longitudinally and transversely of the back of the comb to provide a gap for the sitter's ear.

3. A comb including a back which is twisted intermediate its ends so that the end portions lie in planes oblique to each other, each of said back portions having a series of teeth lying in the plane of said back por-

tion, whereby one set of teeth lies in a plane oblique to that of the other set with a gap ¹⁰ between the innermost of the teeth of the sets for spanning the ear of the sitter.

In testimony whereof, I affix my signature.

GEORGE B. CANADA.
